UNITED STATES PATENT OFFICE.

WILLIAM E. SCARLETT, OF EAST LYNN, MASSACHUSETTS.

HEEL-NAILING JACK.

1,265,525.

Specification of Letters Patent. Patented May 7, 1918.

Application filed May 2, 1914. Serial No. 836,014.

To all whom it may concern:

Be it known that I, WILLIAM E. SCARLETT, a citizen of the United States, and resident of East Lynn, county of Essex, Commonwealth of Massachusetts, have invented an Improvement in Heel-Nailing Jacks, of which the following description, in connection with the accompanying drawings, is a specification, like characters on the drawings representing like parts in each of the several views.

In the nailing of heels onto shoes as ordinarily carried out in power machines trouble has been frequently experienced with the crushing and breaking down of the lasts under the thrust of the nailing head; this being due to the fact that the usual nailing machines heretofore in use have not had any adequate means for gaging and accurately determining the position of the last with reference to the height of the heel and the final limit of the stroke of the power head for the various different styles of heels and kinds of lasts. One prime object of the present invention is to provide a heel nailing jack specially adapted for use with means whereby any given last with any selected style and height of heel may be quickly and conveniently positioned and clamped in accurate and definitely known relation to the stroke of the power head whereby the extent of compression by the power head in the pricking and nailing operations can be definitely determined and liability of undue pressure that would be liable to crush the last avoided. A further object is to provide an improved construction of nailing jack or support adapted to be manipulated with ease and precision for positioning the last with the shoe thereon in proper relation to the operative parts of the nailing machine, the shoe holding devices being conveniently and quickly adjustable in any direction as required for engaging various styles and sizes of shoes. This improved nailing jack or support which constitutes my invention has as a central feature thereof a self contained mechanism adapted by a single manual throw to adjust the jack post with the last thereon upward to a predetermined amount as required for bringing the heel against the nailing plate. Still further features of the invention have to do with an improved construction of toe rest and mounting therefor, and with an improved construction

of head for the jack post and a self adjusting jack pin carried thereby. The above and other objects and features of the invention will be better understood from the following detailed description taken in connection with the accompanying drawings and will be thereafter pointed out in the appended claims.

Referring to the drawings:

Figure 1 shows in side elevation the operative parts of a machine and nailing jack constructed in accordance with my invention;

Fig. 2 is a fragmentary detail showing my improved two-step locking device as seen from the front of the machine;

Fig. 3 is an enlarged side view of the nailing jack removed;

Fig. 4 is a plan view of the jack;

Fig. 5 is a front view thereof;

Fig. 6 shows a further enlarged view of the jack post head; and

Fig. 7 is a sectional detail on line 7—7 of Fig. 3.

At the rear of a suitable stand or base 1 is fixed a block 2 from which rises a guide column 3, on which is slidably fitted a depending sleeve 4 of a head 5 from the front of which projects a usual nailing plate and nail templet guide 6. The vertical movement of head 5 is controlled by a hand lever 7 fulcrumed at 8 near the rear of the machine and extending toward the front thereof, this lever being connected by a link 9 with the depending sleeve 4 of the head. The head 5 is normally held yieldingly at its upper limit of movement by a stout coil spring 10 acting between the top of the column 3 and a recessed seat in the head. The power drive mechanism, a part of which is indicated at 11, may have a usual prick head, and a drive head 12 operable in the usual manner.

I provide means whereby the head 5 bearing the nailing plate may be locked in a definite preliminary lowered position where the nailing plate is adapted to serve as a backing to permit the heel to be clamped in place on the shoe under the action of the jack as presently described; this preliminary locking of the head 5 being so arranged with reference to the range of movement of the power head that as the power head descends for the pricking operation, the head is forced farther down by a predetermined

75

105

110

amount and locked in a second position where the pressure upon the heel is suitable for the nailing operation without being excessive or apt to crush the last. As a suitable means for this end I show a spring bar 13 with a catch head 14 at its lower end equipped with two ledges 15, 16 one above the other in step relation, the distance between these ledges determining the extent 5 of the final compression of the heel after its first adjustment against the nailing plate. These locking ledges are adapted to engage underneath a fixed abutment 17 secured to or forming a part of the block 2. The spring locking bar 13 is adjustably held to the head 5 by an elongated slot and bolt connection as seen at 18, the interengaging surfaces being preferably serrated as seen at 19. The lower end of the catch head 14 is beveled as seen at 20 to be engaged by the end of a lever 21 fulcrumed at 22 with an operating handle 23 for tripping the lock, this lever being normally held in inoperative position as shown, by a spring 24. Suitable means 20 for holding the head 5 from turning is provided, this being shown as a lug 25 at the back of sleeve 4 which is slidably fitted to a post 26 upstanding from the block 2. Turning now to the means for supporting the 30 shoe in operative relation to the nailing mechanism, I provide a slide base 27 shown as equipped with lateral flanges 28 to engage guide ways 29 on the stand 1 for in and out movement relative to the head and 35 its mounting. The slide base 27 has at its inner side an upright extension 30 formed with a vertical bore in which is slidably fitted the jack post 31. This post has its lower portion formed with coarse threads as 40 seen at 32 which are engaged with a sleeve nut 33 fitted in bearings of the upright 30. This nut 33 is equipped with a spur pinion 34 which is operated by a gear 35 mounted on a stud 36 fixed in the base. The gear 35 45 is preferably considerably larger than the gear 34 being shown as in two to one ratio. This taken in conjunction with the coarse threads 32 of the jack post permits a substantial degree of jack post adjustment with 50 a relatively small amount of turning of the gear 35. The gear 35 is equipped with spaced apart holes 37 selectively engageable by a pin 38 carried by and operative in, a hand lever 39 journaled on the stud 36. The 55 pin 38 is slidably fitted in the lever 39 being carried by a trip lever 40 fulcrumed at 41 on the top of the lever 39 with an interposed spring 42 acting to normally press the pin 38 into one of the holes that may be in 60 register therewith. By the shiftable clutch connection thus obtained of the lever 39 with the gear 35, it is possible to so set the lever with reference to said gear that by swinging it from the initial position thus established 65 to some definite angular extent, *e. g.*, to its

final limit of throw, the jack post with the shoe thereon will be moved up by a predetermined variable amount that may be desired. To hold the toe rest and guide in proper relation to the jack post I provide a 70 bracket 43 which may be secured at its rear end to the upright 30 as seen at 44 and it is secured intermediate its length to the upper end of the stud post 36 which is extended for this purpose, the bracket 43 being spaced 75 above the gear 35 by a spacing block 44 enough so that the operating lever has clearance thereunder. The bracket 43 has an elongated slot 45 at its projecting front portion in which is fitted a reduced end 46 of 80 a threaded post 47. A nut 48 engaged with the lower threaded part of the post 47 serves as an adjustable backing for clamping the post 47 to the bracket by means of a nut 49 underneath which is equipped with an operating handle 50. Thus by loosening the nut 49 the toe support post 47 may be adjusted in and out to accommodate different sizes of shoes, and by proper adjustment of the nut 48 it is possible to so arrange the operation 85 of the nut 49 that when it is in clamping position its handle 50 will extend in a direction so as to be out of the way. The upper portion of the post 47 has slidably fitted thereon a head 51 which is held from turning 90 by a slidable key engagement with an extended key way of the post as seen at 52. This head 51 rests on a nut 53 threaded on the post 47 and by the manipulation of said nut may be adjusted up and down as required for different styles and sizes of shoes. The head 51 has at its top a cushion rest 54 for the toe, of suitable width and it is equipped with opposite lateral bearings 55 for the journals of swinging arms 56 which 100 extend up to constitute side guides 57 for the front portion of the shoe. These arms 56 have at their lower ends nuts 58 engaged by threads of a right and left hand screw 59, the central portion of which is journaled at 105 60 on the head 51. Thus by turning this screw the guides 57 may be properly adjusted so that they are in position to aline, one rights and the other lefts of shoes as the foreparts thereof are brought against one 110 glide or the other as the case may be. 115

The jack post 31 may be held against turning by a transverse pin 61 therein, the projecting head of which engages an elongated vertical slot 62 in the top of the upright 30. A jack post head 63 is fixed to the top of the post 31 and it has pivoted at the back thereof at 64 a rest piece 65 for the top of the last. This rest piece is adapted to be 120 adjusted angularly to fit the surface of the last by means of a screw 66 threaded through a forward extension 67 of the head 63 and acting upon a depending portion 68 of the rest which is guided between cheeks 68' of the head. I preferably provide means 125 130

whereby the last pin 69 can adjust itself laterally to accommodate irregularities in the holes of the lasts while being still held rigidly upstanding and for this purpose the last pin has a T-head 70 engaging a transverse undercut groove in the rest whereby the pin may slide laterally to the requisite extent and still be held secure against any swinging or vibrating tendency. To limit this transverse movement of the last pin, a slot 71 is formed in the head thereof and into this extends the end of a threaded pin 72 fitted in the depending portion 68 of the rest. A receiver for engaging the back of the shoe and positioning it on the jack is indicated generally at 73 with lateral cheek plates 74 adapted to be adjusted up against the sides of the shoe by an adjusting screw 75. The receiver as a whole is adjustable in and out from the block 2 by an adjusting screw 76. The details of this receiver form no part of the present invention and are claimed in my co-pending application, Serial No. 33,166, filed June 9, 1915.

It may now be understood that in use the handle 7 will be operated to press down the head 5 with the nailing plate 6 against the tension of spring 10 until the first locking notch 15 snaps under the abutment 17. Then the handle 39 will be adjusted relative to the gear 35 by engaging the pin 38 in the proper hole 37 so that by giving a predetermined swing to the handle it will bring the heel as it is set in place on the shoe resting on the jack into proper relation or preliminary pressing engagement with the nailing plate 6, the proper position of the handle 39 and gear 35 for this purpose of course being different and varied as required for different heights of heels and sizes and styles of shoes. Thereupon the heel being brought to the proper position by operation of the handle 39, the power head 11 descends to prick the holes, at the same time pressing down upon the nailing plate to give the final compression to the heel and as this occurs the second step 16 of the locking bar 13 snaps in place under the abutment 17, holding the nailing plate down to keep the heel properly compressed as the nails are driven. In these operations it will be noted that it is possible to determine the extent of secondary or power compression of the heel with exactness, since the preliminary compression as effected by the operation of the jack handle 39 is to a definite and predetermined extent and of course the extent of movement of the power head is likewise a definite invariable quantity. It will be noted that by reason of the elevated position of the bracket 43 which holds the rest for the front portion of the shoe, the operating lever 39 can have a full range of movement and be operated to the best advantage. It will further be noted that my improved means for adjusting the toe rest and for adjusting the rest at the head of the jack post permit the shoe to be positioned quickly and accurately for the heelng operation. I am aware that various of the details of the invention can be varied without departing from the spirit thereof and I therefore desire the present embodiment to be considered as illustrative and not restrictive, referring rather to the appended claims to indicate the scope thereof.

Having described my invention, what I claim as new and desire to secure by Letters Patent is:

1. In a heel nailing machine, a jack post adapted to hold a shoe with a heel thereon in operative relation to a nailing plate, and an operating device for said jack post adjustable to different initial positions to raise it vertically to variable and predetermined positions at a single full movement of said operating device from a selected initial position to a determinate limiting position for bringing heels of different heights to operative position. 90
2. In a heel nailing machine, a jack post mounted to hold a shoe with a heel thereon, and means for raising and lowering said jack post consisting in a gear, an operating handle mounted concentric therewith, and means for variably connecting said operating handle with said gear for moving said jack post upward to variable predetermined positions at the limit of throw of said handle for the purpose stated. 100
3. Apparatus of the kind described, comprising a jack post for supporting a last with a shoe thereon, means for moving said post endwise, an adjustable handle mounted to swing horizontally for operating said post moving means, and means for supporting the front portion of the shoe having a mounting offset from said jack post and elevated to clear said handle to permit swinging thereof for adjusting and operating movements. 105
4. Apparatus of the kind described, comprising a base having an upright formed to constitute a guide for a jack post, a jack post having a rest at its top to receive a last, fitted to slide in said upright, the lower portion of said jack post being threaded, a nut fitted to engage the threads of said jack post, gearing for operating said nut and a handle to operate said gearing having means for selective engagement therewith in different positions at will. 115
5. Apparatus of the kind described, comprising a support having a jack post slidably fitted therein, operating means for adjusting said jack post longitudinally in said support disposed adjacent the base of said support, and a rest for the front portion of the last having a bracket mounting carried by said support and extending over said operat- 125

ing means for the jack post so as to clear the same in all positions of the movement thereof.

6. Apparatus of the kind described, comprising a base having an upright extending therefrom, a jack post fitted for adjustment in said upright, operating means for adjusting the jack post longitudinally in said upright disposed adjacent said base, a bracket extending out from said upright over said operating means to clear the same, and means for supporting the front of the last adjustably carried by said bracket.

7. Apparatus of the kind described, comprising means for supporting the back part of a shoe in position for heel nailing and

means associated therewith for supporting and alining the forepart of the shoe, said alining means consisting in a pair of upstanding spaced apart guides with means for simultaneous adjustment whereby one is in position to aline rights and the other lefts of any style or size of shoe. 20

In testimony whereof, I have signed my name to this specification, in the presence of 25 two subscribing witnesses.

WILLIAM E. SCARLETT.
